UNITED STATES PATENT OFFICE.

ERNEST WILDHABER, OF BROOKLYN, NEW YORK, ASSIGNOR TO NILES-BEMENT-POND COMPANY, OF NEW YORK, N. Y., A CORPORATION OF NEW JERSEY.

GRINDING HELICOIDAL SURFACES.

Application filed July 13, 1923. Serial No. 651,394.

My invention relates to methods of grinding helicoidal surfaces and particularly to methods of grinding worms having threads provided with involute helicoidal surfaces.

5 One object of my invention is to provide a method of grinding worm threads that shall comprise a minimum number of operations and that shall grind the sides of a worm thread to involute helicoids in an efficient manner.

Another object of my invention is to provide a method of the above indicated character for grinding a worm thread by the flat side of a grinding wheel in such manner that 15 only one angular setting of the wheel is required in order to grind involute helicoids on the sides of the thread.

A further object of my invention is to provide a method that shall grind involute helicoids on the sides of worm threads by means 20 of a grinding wheel having a flat grinding surface, the grinding wheel being angularly adjusted about an axis in the direction of the shortest line between the axis of the wheel and the axis of the worm in accordance with 25 the involute helicoids and the wheel, if necessary, being adjusted horizontally and vertically to effect correct engagement between the wheel and the blank.

30 It is customary, at the present time, to grind involute helicoids on the sides of a worm thread by means of a grinding wheel having its axis in the plane of the shortest line between the axis of the wheel and the axis of the worm being ground. In such case it is necessary, in order to grind involute helicoids, to angularly adjust the grinding wheel not only about a single axis, but also to angularly adjust the grinding wheel about 35 a second axis normal to the first. Each angular adjustment must be made very accurately, inasmuch as the accuracy of the involute helicoid being cut depends upon the accuracy of such adjustments.

45 In forming involute helicoids on the sides of worm threads in accordance with my method, the grinding wheel is angularly adjusted about only one axis, namely an axis in the direction of the shortest distance between the blank axis and the wheel axis. Preferably the shortest line between the blank axis and the wheel axis is located in a horizontal plane. The angular adjustment about such axis must be accurately made, 50 inasmuch as the helicoid being cut is depend-

ent upon the angle at which the grinding surface is set. The grinding wheel is adjusted in a vertical plane and also in a horizontal plane. However, the vertical and the horizontal adjustments do not need to be made 60 with the accuracy of the angular adjustment. The vertical and the horizontal adjustments effect only the fillet formed at the bottom of the worm thread.

65 In the accompanying drawings:

Figure 1 is a plan view of a grinding wheel in engagement with a worm.

Fig. 2 is an end elevational view of the worm and wheel shown in Fig. 1.

Fig. 3 is a diagrammatic plan view of a 70 grinding machine adapted to operate in accordance with my invention.

Fig. 4 is a front elevational view of the machine shown in Fig. 3.

Referring to Figs. 1 and 2 of the drawings, 75 a grinding wheel 1 is shown in engagement with the thread 2 on a worm 3. The worm 3 is assumed to rotate on an axis $c-c$ and the grinding wheel 1 is assumed to rotate on an axis $c'-c'$. The wheel shown is a cup-shaped grinding wheel having an annular grinding ring extending between the limiting circles 4 and 5, as best shown in Fig. 2 of the drawings. The grinding surface is perpendicularly disposed with respect to the 80 axis $c'-c'$ of the grinding wheel. Inasmuch as only an annular ring near the edge of a flat grinding wheel is utilized during the 85 grinding operation, it is considered in the present invention that a cup-shaped grinding wheel is the equivalent of a grinding wheel having a flat grinding surface.

An involute helicoidal surface may be considered as composed of a number of straight lines which are all tangent to a predetermined helix. Moreover, tangential planes may be drawn with respect to the involute helicoidal surface which contacts with the surface not merely at a point, but in a straight line. Consequently a grinding 100 plane may be placed in such a tangential plane to an involute helicoid for grinding the involute helicoid. For a more complete explanation as to the properties of an involute helicoid, reference may be made to my co-pending application Serial No. 543,385, filed March 13, 1922.

105 The intersection of a plane perpendicular to the axis of an involute helicoid with the involute helicoidal surface always produces 110

an involute. The base cylinder of the involute has the same diameter as the helix upon which the involute helicoid is formed and in other words the base cylinder of the involute helicoidal surface is identical with the cylinder on which the helix is wound.

In Fig. 2 of the drawings, the base cylinder of the involute helicoid is indicated by a dot-and-dash circle *b*. The line 6—7 along which the grinding wheel engages a thread of the worm is indicated in Figs. 1 and 2 of the drawings. Such line 6—7, it will be apparent, is tangent to the base circle *b* in order to form an involute helicoid on the side 10 of the worm thread. The depth circle 9 or the bottom of the worm thread 2 is indicated in Figs. 1 and 2 of the drawings. As heretofore set forth, it is to be understood that the grinding surface on the wheel 1 is perpendicularly disposed with respect to the axis 15 *c'—c*.

In Fig. 2 of the drawings, it will be noted the axis of the grinding wheel 1 is elevated above the axis of the worm 3. If two lines 20 such as the axis *c—c* of the worm 3 and the axis *c'—c'* of the wheel do not intersect, then the shortest connecting line between the two axes must be a perpendicular line connecting them. In Figs. 1 and 2 of the drawings, the 25 shortest connecting line between the axis *c—c* and the axis *c'—c'* is indicated by the reference character 10. In Fig. 2 the dotted line 11 is assumed to indicate the position of the grinding wheel 1 when so set that the intersection point of the grinding surface and the axis of the grinding wheel is in the line 30 10. The line 10 is assumed to be the shortest distance between the axis *c—c* and the axis *c'—c'*. In the position of the wheel, as indicated by the dotted line in Fig. 2 of the drawings, the grinding wheel extends to the base circle 9 and the axis of the grinding wheel is in the position *c"—c'*. In such position of the grinding wheel, it will be noted 35 only a very small portion of the line 6—7 is covered by the grinding surface. Accordingly, in order to grind along the line 6—7 it will be necessary to advance the grinding wheel towards the axis *c—c* of the worm. In 40 advancing the grinding wheel towards the blank axis, a distance such that the line 6—7 will be covered by the grinding wheel, a very deep fillet would be formed at the bottom of the worm thread. Accordingly, it would be 45 impractical to grind a worm by a grinding wheel which is only adjusted about the line of shortest distance between the axis of the blank and the axis of the wheel. As heretofore set forth, it is possible to effect a second 50 angular adjustment of the wheel about a vertical axis as the parts are disposed in Figs. 1 and 2, but such adjustment must be effected with extreme accuracy.

In order to grind along the line 6—7 and 55 not be compelled to effect a second angular

adjustment of the grinding wheel, the grinding wheel may be raised above the axis of the worm and then moved towards the worm to the position indicated by full lines in Fig. 2 of the drawings. In describing the position of the grinding wheel with respect to the worm, it has been assumed that the grinding axis *c—c* and the worm axis *c'—c'* are initially in a horizontal plane. In such case the angular adjustment of the wheel would necessarily be about an axis in the direction of the line 10 which is a horizontal line connecting the axes *c—c* and *c'—c'*. The wheel axis is raised vertically and is moved horizontally towards the worm until a position is reached as indicated in Fig. 2 of the drawings by the full lines.

Referring to Figs. 3 and 4 of the drawings, a machine for grinding a worm in accordance with my invention is diagrammatically illustrated. In Figs. 3 and 4 of the drawings, a grinding wheel 15 is shown in engagement with a thread 16 on a worm 17. The worm 17 is mounted on a spindle 18, which is rotated in any suitable manner. Any suitable means (not shown) may be provided for effecting longitudinal feeding of the worm in accordance with the rotation thereof. The worm and spindle are supported on a slide 19 which is longitudinally movable on a slide 20. The slide 19, as shown in Figs. 3 and 4, is movable longitudinally with respect to the machine. The slide 20 is directly mounted on the frame 21 of the machine and is moved by means of a gear and rack mechanism 22, as indicated in Fig. 4 of the drawings. The slide 20 is moved transversely with respect to the machine and may serve not only to bring the blank or worm into engagement with the grinding wheel, but also, if so desired, to permit indexing under certain conditions.

The grinding wheel 15 is mounted on a shaft 23 which is provided with suitable bearings on a base plate 24. The base plate 24 is rotatably mounted on a vertical slide 25. Any suitable means may be provided for angularly adjusting the position of the base plate 24. In Figs. 3 and 4 of the drawings, a worm and worm wheel mechanism 26 is shown for adjusting the angular position of the base plate. It is to be understood that the base plate 24 is adjusted about an axis *d—d* which is perpendicular to the axis of the grinding wheel. In Fig. 3 of the drawings, it is apparent that the axis *d—d* is perpendicular to the axis of the grinding wheel. In Fig. 4 of the drawings, it will be noted the projection of the axis *d—d* is perpendicular to the axis of the worm.

The vertical slide 25, which is mounted on a portion 27 of the machine, is moved by means of any suitable mechanism, as for example, a bevel gear mechanism 28.

In grinding a worm in accordance with

my method, the grinding wheel 15 is angularly adjusted by means of the worm mechanism 26 in accordance with the involute helicoid which is to be cut on the sides of the worm thread. The vertical slide 25 is adjusted in order that the grinding wheel may cover the contact line on the worm thread as indicated in Figs. 1 and 2 of the drawings. The slide 20 is then operated to move the worm into engagement with the grinding wheel. No means has been shown for advancing the slide 19 in accordance with the rotation of the worm and the pitch of the worm thread, inasmuch as such mechanisms are well known.

The grinding wheel 15 is operated in any suitable manner, as by means of an electric motor 30. The motor 30 is mounted on the plate 24 and carries a pulley 31 which is connected by a belt 32 to a pulley 33 which is mounted on the shaft 23.

It will be understood that such changes and modifications may be made in my invention as fall within the limits of the appended claims.

What I claim is:

1. The method of grinding an involute helicoidal surface on a blank, which consists in providing a grinding wheel having a flat grinding surface, in effecting an angular adjustment and two rectilinear adjustments between the wheel and the blank so that the shortest connecting line between the axis of the blank and the axis of the wheel is outside the surface of the grinding wheel, and in rotating the wheel and the blank while effecting relative feeding movement in accordance with the pitch of the helicoid.

2. The method of grinding an involute helicoidal surface on a blank, which consists in providing a grinding wheel having a flat grinding surface, in positioning the axis of the blank and the axis of the wheel in parallel relation, in effecting one angular adjustment of the wheel and two rectilinear adjustments between the wheel and the blank so that the shortest line between the axis of the blank and the axis of the wheel is outside the surface of the grinding wheel, and in rotating the wheel and the blank while effecting relative feeding movement in accordance with the pitch of the helicoid.

3. The method of grinding an involute helicoidal surface on a blank, which consists in providing a grinding wheel having a flat grinding surface, in positioning the axis of the blank and the axis of the wheel in parallel relation, in angularly adjusting the grinding wheel about an axis extending in the direction of the shortest distance between the axis of the wheel and the axis of the blank, in effecting rectilinear adjustments perpendicularly and parallelly to the shortest distance between the axis of the

wheel and the axis of the blank, and in rotating the wheel and the blank while effecting relative feeding movement in accordance with the pitch of the helicoid.

4. The method of grinding an involute helicoidal surface on a blank, which consists in providing a grinding wheel having a flat grinding surface, in angularly adjusting the wheel about an axis parallel to a line perpendicular to the blank axis, in effecting rectilinear adjustments between the wheel and the blank perpendicularly and parallelly to the shortest connecting line between the wheel axis and the blank axis, and in rotating the blank and the wheel while effecting relative feeding movement in accordance with the pitch of the helicoid.

5. The method of grinding an involute helicoidal surface on a blank, which consists in providing a grinding wheel having a flat grinding surface, in positioning the axis of the blank and the axis of the wheel in parallel relation, in angularly adjusting the wheel about an axis extending in the direction of the shortest line between the axis of the wheel and the axis of the blank, in relatively adjusting the wheel and the blank in a direction perpendicular to said shortest line, and in rotating the wheel and the blank while effecting relative movement in accordance with the lead of the helicoid.

6. The method of grinding an involute helicoidal surface on a blank, which consists in providing a grinding wheel having a flat grinding surface, in positioning the axis of the blank in a horizontal plane, in angularly adjusting the grinding wheel in accordance with the lead of the helicoid about a horizontal axis perpendicular to the axis of the blank, in relatively adjusting the blank and the wheel in a horizontal plane, in adjusting the wheel axis in a vertical plane above or below the axis of the blank, and in rotating the blank and the wheel while effecting relative feeding movement in accordance with the pitch of the helicoid.

7. The method of grinding an involute helicoidal surface on a blank, which consists in providing a grinding wheel having a flat grinding surface, in positioning the axis of the wheel and the axis of the blank in parallel relation, in angularly adjusting the grinding wheel in accordance with the lead of the helicoid about an axis parallel to a line perpendicular to the axis of the blank, in relatively adjusting the wheel and the blank towards and away from each other, in adjusting the axis of the wheel perpendicularly to a line perpendicular to the blank axis, and in rotating the wheel and the blank while effecting feeding movement in accordance with the pitch of the helicoid.

8. The method of grinding an involute helicoidal surface on a blank, which consists in providing a grinding wheel having a flat

grinding surface, in angularly adjusting the wheel about an axis parallel to a line perpendicular to the axis of the blank, in adjusting the blank and the wheel away from and toward each other, in adjusting the wheel axis with respect to the blank axis in a plane perpendicular to the axis of angular

adjustment, and in rotating the wheel and the blank while effecting relative movement in accordance with the lead of the helicoid. 10
In testimony whereof, I hereto affix my signature.

ERNEST WILDHABER.
